UNITED STATES PATENT OFFICE

CHARLES F. CARPENTER, OF SCHENECTADY, NEW YORK, ASSIGNOR TO GENERAL ELECTRIC COMPANY, A CORPORATION OF NEW YORK

MOTOR-STARTING SWITCH

Application filed October 21, 1926. Serial No. 143,270.

My invention relates to improvements in electric switches and in particular to the type of motor starting switches known in the art as starting compensator switches which act to connect the motor to the source of supply first through reduced voltage taps of an autotransformer for starting, and then directly to the source for running.

More particularly, the invention is directed to improvements of the starting compensator on which William E. Paul obtained U. S. Letters Patent No. 1,554,024, dated September 15, 1924. In the system of the Paul patent the motor starting contacts and the running contacts are operated by separate switch levers and these levers are interlocked to prevent improper sequence of operation. One of the objects of my invention is to provide a simple and effective arrangement whereby moving a single operating handle in one direction effects the desired sequence of operation of the motor controlling switch contacts. One set of contacts is provided for closing the neutral of the autotransformer, another set is provided for establishing the starting connections for the controlled motor through the autotransformer and the third set is provided for establishing the running connections through cooperation with the starting contacts. Means including link mechanism connecting the starting, neutral and running contacts provides mechanism whereby moving the operating handle in one direction first closes the starting contacts with the neutral contacts closed so that the motor is connected to a source of supply through the reduced voltage taps of the autotransformer, then the neutral contacts are opened leaving the motor connected to the source through the autotransformer now serving as a reactor, and finally the running contacts are closed so as to connect the motor directly to the source through the starting and the running contacts in such a manner that the autotransformer does not take any charging current.

For a better understanding of the invention, reference is had to the accompanying

drawings in which Fig. 1 is a perspective view of a compensator unit assembly with the switch in accordance with the invention mounted in a supporting framework with the operating handle on the outside of the front panel thereof. The assembly also shows a supporting shelf for an oil well (not shown), and shows a space within the framework for mounting the autotransformer. Fig. 2 is a detail of a perspective view of the assembly of Fig. 1 taken from a different angle in order to more clearly show the operating mechanism for the switch contacts. Fig. 3 is a very simplified system of motor control in which the switch of the invention may be employed to advantage. Figs. 4, 5 and 6 are skeleton views of the switch mechanism in the off or open position of the switch handle, the starting position and the running position respectively, and Fig. 7 and Fig. 8 show the guide in which the handle of the controller operates so as to cause the operator to pause at the start position.

Referring first to Fig. 3, the electric motor 10 to be controlled is arranged to be connected to the three phase source of supply 11 through the starting switch, the contacts of which are indicated diagrammatically. The switch comprises one set of contacts 12 which may be termed the starting set, the set of contacts 13 which is arranged to normally close the neutral of the three phase autotransformer 14, and the third set of contacts 15 which may be termed the running set. The starting, neutral, and running sets of contacts are interconnected in such a way as will be hereinafter explained in connection with the other figures of the drawings, that a single operating handle is effective by a unidirectional movement thereof to first close the starting contacts and thereby connecting the motor to the source through the reduced potential taps of the autotransformer to which the motor is permanently connected. The next operation effected by the forward movement of the operating handle effects the opening of the neutral closing switch 13, leaving the starting set of contacts 12 closed, thereby maintaining

the connection of the motor to the source and causing the autotransformer to serve as a reactor to maintain the applied voltage to the motor. The next operation effected by the forward movement of the operating handle will effect the closing of the running set of contacts 15, thereby connecting the motor to the source through the starting and running sets of contacts, leaving the autotransformer connected in such a way that it does not take any charging current from the line.

By referring to Figs. 1 and 2 it will be seen that the switch mechanism for controlling the starting of the motor is mounted within a supporting framework 16 and that the operating handle 17 is disposed on the outside of a panel supported by this framework. An oil well (not shown) which surrounds the switch contact mechanism whereby this contact mechanism may be immersed in oil so as to reduce the effect of arcing at the switch contacts, is arranged to be supported on the insulators 18 forming a part 25 of a shelf supported by the framework. This shelf is arranged to support the oil well in position when the oil well is lowered to permit inspection of the switch contacts and when the switch is in operating condition the oil well is adapted to be secured in an elevated position so that the switch contacts are immersed in the oil. The lower part of the framework provides a space 19 within which the autotransformer (shown in Fig. 3) may be securely mounted in a convenient position with respect to the switch contact mechanism. The whole assembly thus forms a complete unit which may be manufactured and wired ready for installation with the customer's source of supply and the motor to be controlled. The interconnections between the autotransformer and the oil switch are not shown in Figs. 1 and 2, since it is believed that those skilled in the art will readily understand the same from a consideration of Fig. 3.

It will be seen from reference to Fig. 2 and more particularly in connection with Figs. 4 to 6, inclusive, that the starting set of contacts is mounted so as to be operated by a shaft 20 and the running contacts are mounted so as to be operated by a parallel disposed shaft 21, these shafts being secured in the framework 16. Link mechanism, including the link 22, connects the operating handle 17 with the shafts 20 and 21 and the switch contacts so that a forward movement of the operating handle will effect the operations above stated. An automatic release mechanism 23 is provided for effecting the release of the switch contact mechanism so that the sets of contacts return to their respective positions indicated in Fig. 3 in response to abnormal circuit conditions. The details of this releasing mechanism are not

shown, since this forms no part of my invention and furthermore, arrangements of this sort are old and well known to those skilled in the art.

Reference is now had more particularly to Figs. 4 to 6, inclusive, for an explanation of the details of construction and arrangement whereby the sequential operation of the sets of contacts is secured. It will be seen that the starting set of contacts 12 comprises three movable contact members, each of which is arranged to make engagement with a pair of stationary contacts. The running set of contacts 15 is of similar construction and each contact member of the set is arranged to make engagement with a pair of stationary contacts, as shown. Each contact member of the two sets 12 and 15 is similarly mounted for reciprocatory movement with respect to its operative shaft. Thus, the contact member 15 is pivotally suspended from an operating rod, of which the part 24 is of insulating material so as to insulate the contact member from its operating shaft and the other parts of the switch mechanism. The insulating part 24 is secured to an operating rod 25 which is pivotally connected with a lever 26 secured to the operating shaft 21. The other contacts of this set are similarly connected with the shaft 21 and it will also be seen that the contact members of the starting set 12 are individually connected to the operating shaft 20 by similar mechanism.

The neutral closing set of contacts comprises the switch member 27 which is pivotally connected with a post 28 of insulating material, which is in turn pivotally connected with one arm of a bell crank lever 29. The other end of this bell crank lever is connected by means of a link 30 with the lever 31 secured to the operating shaft 21. The bell crank lever 29 is mounted upon the shaft 20 and is arranged so as to rotate with respect thereto. The contact member 27 is also pivotally connected with a bridging member 32, which is pivotally connected to the insulating support or post 33. The other end of this lever 32 is connected to one end of the terminals of the autotransformer 14 as indicated in Fig. 3 and the contact member 27 together with its corresponding set of stationary contacts form the set of contacts 13 which establish the neutral of the autotransformer.

The operating handle 17 is pivotally mounted with respect to the shaft 34 and connected through a universal joint 35 with the operating rod 36. This operating rod is pivotally mounted in one arm of what constitutes in effect a bell crank lever 37, to which the heretofore referred to link 22 is also pivotally connected. The other arm of this bell crank lever is connected with the shaft 21 by means of a link 38 which has one end thereof pivotally connected with the

lever 39 secured to the operating shaft 21. The bell crank lever 37 is mounted for rotation on the shaft 40 and the spring 41 mounted on this shaft provides a means for biasing the bell crank lever and the sets of switch contacts to their respective positions indicated in Figs. 1, 2, 3 and 4.

As before stated, Fig. 4 shows the relative position of the various parts of the switch mechanism in their respective positions preparatory to the operation of the handle 17 to effect the final connection of the controlled motor 10 directly to its source of supply 11. It will be seen that the set of starting contacts 12 is in its normal open position and the running set of contacts 15 is also in its normal open position. The neutral closing switch mechanism is in its normal closed position. When the handle 17 is rotated clockwise to the position indicated in Fig. 5, the various parts of the switch mechanism will assume their respective positions indicated in Fig. 5. It will be seen that through the link 22 the shaft 20 has been rotated so as to effect the closing of the starting set of contacts 12, and it will also be seen that through the link 38 the running set of contacts 15 is moved slightly farther away from its corresponding stationary contacts. It will also be seen that although the shaft 21 is rotated slightly through the action of the link 38, nevertheless the neutral closing set of contacts 13 will remain in the closed position, a slightly greater pressure being applied to these contacts. This is by reason of the interconnection of the shaft 21 with the neutral closing contacts 13, by means of the link 30 and the bell crank 29. It will be observed that the right-hand end (Figs. 4, 5 and 6) of the link 22 is of hook shape so that a continuation of a clockwise forward movement of the operating handle 17 will effect no further rotation of the shaft 20, although the bell crank lever 37 will be rotated from its position indicated in Fig. 5 to its position indicated in Fig. 6 when the handle 17 has been operated to its full extent of movement. During this final movement, the link 38 comes into play to effect counter clockwise rotation of shaft 21. This arrangement, therefore, provides for an initial movement of the starting contacts to their closed positions and limits the pressure applied to these contacts during a continuation of the movement of the operating handle during which the neutral closing switch is first opened and then the running set of contacts closed, as is indicated in Fig. 6.

The neutral closing switch is first opened after the operation has proceeded to the point indicated in Fig. 5 by reason of the rotation of the shaft 21 in a counter-clockwise direction through the action of link 38. This counter-clockwise rotation of

the shaft 21 first effects through the link 30 a counter-clockwise movement of the bell crank lever 29 and this movement effects the opening of the neutral closing contacts 13. A continuation of the counter-clockwise movement of the shaft 21 as the operating handle is advanced to the position indicated in Fig. 6, causes the running set of contacts 15 to be operated into engagement with its respective stationary contacts. When this operation has been completed, the spring 41 has been wound up so as to place the mechanism under a strain tending to open the starting and the running set of contacts and the closing of the neutral controlling set of contacts. The strain of the spring 41 is resisted by the pivoted catch 42 which is under the control of the relay 23 indicated in Figs. 1 and 2. This catch is also under the control of a manually operable tripping button 43 which provides a means whereby the motor may be disconnected from the source of supply at the will of the operator without forcibly moving the handle 17 in the opening direction.

It will be seen from the above that I have provided a simple and effective mechanism whereby the starting, the running and the neutral contacts may reciprocate in parallel planes and whereby the oil switch type of contacts and contact construction may be employed. It will also be observed that the interconnections between the sets of contacts, the parallel operating shafts 20 and 21 and the operating handle 17 are such that a single handle is effective to cause the desired sequence of operation of the various sets of contacts. It will also be observed that the mechanism is such that the handle 17 may be rotated in substantially a continuous forward movement, thereby rendering the operation very simple so that unskilled operators will be unable to make mistakes in effecting the starting of the motor.

While my invention is particularly applicable to the starting of alternating current motors of relatively large capacity, nevertheless the invention is also applicable to the starting and control of electric motors generally, as will be understood by those skilled in the art from a consideration of the foregoing.

In order to insure that the handle 17 will be moved to the definite starting position and that this exact position will be understood by the operator, I have provided the arrangement shown in Figs. 7 and 8 which show respectively the side and plan views of the guide for the handle 17. This guide comprises the side plates 44 and 45 of the shape shown so as to form a slot between them similar to a portion of the familiar H slot of automobile gear shift mechanisms. The resiliently mounted detent 46 serves to

direct the overhanging guide lug 48 extending from the operating handle 17 into engagement with the shoulder or stop 48 formed in the side plate 44, and thereby 5 retain the handle in the starting position until it is moved sidewise out of engagement with the shoulder 48 and advanced to the running position. In this way the movement of the operating handle 17 is temporarily arrested upon the closure of the starting contacts so as thereby to afford an opportunity for the motor to accelerate before the handle can be moved to close the running contacts. This detent is so constructed and mounted that it is pushed out of the way during a return movement of the handle 17 to the off position and then permitted to return to the position shown in Figs. 7 and 8.

20 What I claim as new and desire to secure by Letters Patent of the United States, is:

1. In an electric switch, a set of switch contacts, a second set of switch contacts relatively movable with respect to said first set, an operating member, connections between said sets of contacts and said member through which a unidirectional movement of said member first closes the first set of contacts and then closes the second set while 25 maintaining the first set closed with substantially no increase in the closing pressure thereof, and means for temporarily arresting the movement of said operating member upon the closure of said first set of contacts.

2. In an electric switch, two relatively movable sets of switch contacts, a separate operating shaft for each of said sets, an operating member, and connections between 40 said shafts and said member through which a unidirectional movement of said member first rotates one of said shafts in one direction to close the first set of contacts and then rotates the other of said shafts in the opposite direction to close the second set while maintaining the first set closed.

3. In an electric switch, two relatively movable sets of switch contacts, an operating member, link mechanism, connecting 50 said sets of contacts with each other and with said member, through which a unidirectional movement of said member first closes the first set of contacts and then closes the second set while maintaining the first set closed, and means for temporarily arresting the movement of said operating member upon the closure of said first set of contacts.

4. In an electric switch, a set of switch 60 contacts, a second set of switch contacts relatively movable with respect to said first set, the said sets of contacts being mounted for reciprocation in parallel planes between definite positions, a third set of contacts 65 relatively movable with respect to said first

and second sets of contacts between definite positions, an operating member, and connections between said member and said sets of contacts through which a unidirectional movement of said member first operates the first set of contacts to one of its definite positions and then operates the third set of contacts from one of its definite positions and finally operates the second set to a corresponding definite position while maintaining said first set in said operated position.

5. In an electric switch, three relatively movable sets of switch contacts, two of said sets being normally in open position and the third set being normally in the closed position, an operating member, and connections between said sets of contacts and said member through which a unidirectional movement of said member first closes the 80 first of said sets of contacts, then opens said third set of contacts and finally closes the second of said sets while maintaining said first set closed.

6. In an electric switch, two relatively movable sets of switch contacts, an operating member, a bell crank lever, link mechanism connecting each of the ends of said lever with one of said sets and through which a unidirectional movement of said member first closes one set of contacts and then closes the second set while maintaining the first set closed, and means for temporarily arresting the movement of said operating member upon closure of said first 90 set of contacts.

7. In an electric switch, three relatively movable sets of switch contacts, a separate operating shaft for the first and the second of said sets, levers connected with said shafts and pivotally connected with respective contacts of said sets, an operating member, a bell crank lever, and link mechanism connecting each of the ends of said bell crank lever with one of said shafts and connecting the operating shaft for the said second set of contacts with the third of said sets of contacts, through which a unidirectional movement of said operating member first operates the first of said sets of contacts, 100 then operates the third of said sets while maintaining the first set in the operated position and then operates the second of said sets.

In witness whereof, I have hereunto set 120 my hand this 20th day of October, 1926.

CHARLES F. CARPENTER.
